UNITED STATES PATENT OFFICE.

WILLIAM T. PYLE, OF NORMAL, ILLINOIS, ASSIGNOR TO SAFETY FOLDING LADDER COMPANY, OF PEKIN, ILLINOIS.

STEP-LADDER.

1,158,716.

Specification of Letters Patent.

Patented Nov. 2, 1915.

Application filed June 8, 1914. Serial No. 843,768.

To all whom it may concern:

Be it known that I, WILLIAM T. PYLE, a citizen of the United States, residing at Normal, in the county of McLean, State of

Illinois, have invented certain new and useful Improvements in Step-Ladders; and I do hereby declare the following to be a full, clear, and exact description of the invention, such as will enable others skilled in the art 10 to which it appertains to make and use the same.

The present invention is directed to step ladders, and has for its object to so construct a device of this character that the 15 same can be easily and quickly folded when not in use.

A further object of the invention is to provide a folding step ladder, which is exceedingly simple in construction, and one 20 which when unfolded will have the desired rigidity.

With these and other objects in view, this invention resides in the novel features of construction, formation, combination and 25 arrangement of parts to be hereinafter more fully described, claimed and illustrated in the accompanying drawing, in which:—

Figure 1 is a front view of the device. Fig. 2 is a side view. Fig. 3 is a front view 30 of the same folded. Fig. 4 is a fragmental side view of the device folded.

Referring to the drawing the numeral 1 designates the side rails of the ladder, which rails consist of spaced strips 2 and between 35 which are pivotally connected the ends of the rungs 3.

Pivotally connected between the upper ends of the rails 1 and to the rearmost strips 2 are brace legs 4 which are held in their 40 spaced operative position by pivotally connected metallic brace bars 5 which are pivoted to the said brace legs, as at 4', and each detachably secured with the opposite leg by a notch in its end, which engages a stud 10 45 on the leg.

A platform 6 is hingedly mounted on the upper ends of the rails 1 by eye bolts 7 mounted on the under face of the said platform 6 and extending downwardly at right 50 angles thereto, which eye bolts are engaged

by hooks 7', the said hooks being mounted in the front strips 2 on the rails 1. These hooks are secured in place by nuts 8 on their ends.

In order that the brace legs and rails may 55 be held in their operative positions jointed side braces 9 are provided, which side braces are pivoted to the rails and to the brace legs so that when the brace legs are swung toward the rails said side braces will be folded. 60

When it is desired to fold the ladder it is only necessary to brake the jointed side bars and to swing the legs 4 against the rearmost strips 2 of the rails 1, it being understood that during this operation the jointed side 65 braces are folded. The brace bars 5 are then disengaged from the studs 10 and one rail 1 is swung toward the other rail about the pivots of the rungs 3. At this time one of the brace legs 4 swings toward the other 70 and the rungs 3 and platform 6 swing into alinement with the folded rails and legs, it being understood that the hook and eye connection between the platform and the rails allows such movement. It is also to be understood that during the folding of the 75 brace legs 4 toward the rails 1 the platform is swung out of a vertical plane into a horizontal plane about the hook and eye connections as pivots. 80

From the foregoing description it may be seen that I have provided a ladder which may be readily folded so as to occupy a very small space, the rails and brace legs being folded upon each other so as to lie in contact 85 and the rungs and platform also swung into alinement with the rails.

I do not wish to be limited to the particular embodiment of my invention, for it is obvious that numerous changes may be 90 made within the scope of the invention as defined by the claim.

What is claimed is:—

A step ladder comprising rails which consists of spaced parallel strips, rungs pivotally secured between said strips, brace legs pivoted to the rearmost of said strips, the said rails being adapted to swing together and the forward faces of the front strips thereof to lie in the same plane, and a plat- 95 100

form mounted on the upper ends of the front strips and adapted to swing so as to lie in front of the front strips and in a plane parallel to the plane of the forward faces of the said front strips when the latter are swung together.

In testimony whereof, I affix my signature, in the presence of two witnesses.

WILLIAM T. PYLE.
